(57) **CLAIM**

The ornamental design for a display positioning device, as shown and described.

DESCRIPTION

FIG. 1 is a front, left perspective view of a display positioning system according to a first embodiment.

FIG. 2 is a bottom, rear perspective view thereof.

FIG. 3 is a top view thereof.

FIG. 4 is a bottom view thereof.

FIG. 5 is a left side view thereof (a right side view being a mirror image of the left side view).

FIG. 6 is a right side view thereof depicting a first disclaimed context (a left side view being a mirror image of the right side view).

FIG. 7 is a front view thereof.

FIG. 8 is a rear view thereof; and,

FIG. 9 is a front, right perspective view thereof depicting the first disclaimed context.

Within the drawings, the broken lines show unclaimed portions of the display positioning device, and form no part of the claimed design.
